UNITED STATES PATENT OFFICE.

THOMAS E. ADAMS, OF PINE BLUFF, ARKANSAS, AND CLARENCE H. HOWARD, OF ST. LOUIS, MISSOURI, ASSIGNEES TO LOCOMOTIVE TENDER FRAME COMPANY, OF ST. LOUIS, MISSOURI, A CORPORATION OF DELAWARE.

LOCOMOTIVE-CRANE UNDERFRAME.

No. 808,534.

Specification of Letters Patent.

Patented Jan. 5, 1908.

Application filed June 12, 1908. Serial No. 488,126.

To all whom it may concern:

Be it known that we, THOMAS E. ADAMS and CLARENCE H. HOWARD, citizens of the United States, residing, respectively, at Pine Bluff, in the county of Jefferson and State of Arkansas, and at St. Louis, in the State of Missouri, have invented a new and useful Improvement in Locomotive-Crane Underframes, of which the following is a specification.

Our invention relates to a locomotive crane underframe which ordinarily consists of a built up wooden or riveted steel framework mounted on wheels adapted to travel along a railroad track and surmounted by a horizontally arranged bed-plate which is pivoted centrally to the underframe and adapted to carry the steam engine, boiler, derrick, hoisting mechanism, and other appurtenances of the crane. On the underframe, between it and the bed-plate, is fixed concentrically with the said pivot, a circular toothed rack which is engaged by a correspondingly toothed wheel or pinion mounted in suitable bearings on the bed-plate, whereby the latter with its appurtenances is adapted to be horizontally revolved about the underframe, the component parts of the underframe with its circular toothed rack being of separate construction secured together by bolts, rivets or, otherwise, whereby the rigidity of the underframe is impaired; and our invention has for its object to provide a strong, rigid, compact, and durable metallic underframe having all its principal parts combined in one piece without the use of fastenings, as hereinafter described and claimed, reference being had to the accompanying drawing, whereon,

Figure 1, is a top plan view of our improved metallic locomotive crane underframe; Fig. 2, a side elevation thereof; Fig. 3, a longitudinal vertical section through the same on line 3, 3, in Fig. 1, and Fig. 4, a transverse vertical section thereof on line 4, 4, in Fig. 1.

Like letters and numerals of reference denote like parts in all the figures.

a represents our improved metallic locomotive crane underframe which is composed preferably, of cast steel integral throughout, and consists in the present case of a horizontally arranged rectangular box-shaped portion *b* of suitable depth constituting the

underframe proper, and surrounding a middle upright tubular portion *c* which peripherally forms the inside wall of the box-shaped portion *b* and projects upward from the closed bottom 1 thereof to a suitable distance above the top of its side walls 2, and end walls 3, which correspond to the side and end sills respectively, of an ordinary metallic locomotive tender or car underframe, the walls 1, 2, and 3, of the box-shaped portion *b* combined with the periphery of the tubular portion *c* being so arranged as to form a receptacle for, and insure the uniform distribution therein of the ballast used for maintaining the stability of the underframe *a* with its wheels and appendages on the railroad track during the operation of the crane.

Centrally within the tubular portion *c*, and united to the inner wall thereof by a series of horizontal arms or radial members 5, is formed the upright tubular bearing 6 for the center pin or pivot 7 (indicated by dotted lines in Fig. 3) of the bed-plate 8 (indicated by dotted lines in Fig. 2), which carries the steam crane and its appurtenances, and is mounted therewith on the underframe *a* in the usual well-known manner, but which not forming part of our invention needs no further description, the tubular bearing 6 having a surrounding horizontal annular surface 6' at the top adapted to form a bearing for the lower face of the central hub (or equivalent member) 9 on the underside of the bed-plate 8 through which the center pin or pivot 7 passes. The tubular portion *c* is formed outwardly at the top with a downwardly inclined surface portion or track 10 which is concentric with the center bearing 6 and adapted to form a bearing for the conical rollers 11 which are interposed between the underframe *a* therewith and a correspondingly inclined bearing surface on the underside of the bed-plate 8 for supporting and maintaining the parallelism of the latter to the underframe *a* at all times.

Depending from the outer circular edge of the overhanging inclined track 10 at the top of the tubular portion *c*, is formed a circular wall or web 12 which is concentric with the wall of the tubular portion *c* and center bearing 6, and united at the bottom to the walls 2 and 3 (preferably at their middle and adjoining ends or corners), and bot-

tom 1 of the box-shaped portion *b*, and to the wall of the tubular portion *c*, by horizontal T-shaped members 13 which are radial to the tubular portion *c*, the whole forming a strong, rigid, compact, and durable structure which being integral is adapted to resist the varying stress of the steam crane without loosening and play of its parts.

Around the wall or web 12 of the tubular portion *c*, and preferably integral therewith, at a suitable height from the top of the box-shaped portion *b*, or body of the underframe *a*, is formed a circular toothed rack 14 which is adapted to be engaged by a correspondingly shaped toothed wheel or pinion 15 (indicated by dotted lines in Fig. 2) mounted in suitable bearings on the bed-plate 8, whereby the latter with its load is revolved about its center pin and bearing 6 relatively to the underframe *a* in the usual well-known manner. Or if desired the rack 14 may be made separately and in segments fixed to the wall 12.

On the underside of the box-shaped portion *b* of the underframe *a* and integral therewith, are formed the brackets 16 to which are fixed the pedestals (not shown) of the axle-boxes; and on the outer face of, and integral with each end sill (or wall 3) of the underframe *a* is formed a draw-bar pocket 17.

We do not limit ourselves to the particular shape and disposition described of the component members of the underframe *a* as these may obviously be varied without affecting the principle of our invention.

What we claim as our invention and desire to secure by Letters Patent is:—

1. In a locomotive crane underframe of the character described, the combination of

a bearing for the pivot pin of the bed-plate 40 of the said crane, and a circular toothed rack concentric with the bearing, for engagement by a toothed wheel rotatably carried by the said plate, the said rack being integral with the said frame, substantially as 45 described.

2. In a locomotive crane underframe of the character described, the combination of a bearing for the pivot pin of the bed-plate 50 of the said crane, and a circular toothed rack concentric with the bearing, for engagement by a toothed wheel rotatably carried by said plate, the said bearing and rack being integral with the said frame, substantially as described. 55

3. A locomotive crane underframe of the character described, comprising a horizontally arranged rectangular box-shaped portion adapted to form a receptacle for ballast, a middle upright tubular portion intersecting and projecting above the box-shaped portion, an upright pivotal bearing located centrally within the tubular portion and united thereto, and a circular toothed rack surrounding the said projecting part of the 60 tubular portion and concentric with the said bearing, all the said parts being integral, substantially as described. 65
